UNITED STATES PATENT OFFICE.

JOHN E. CAPS, OF WILMETTE, ILLINOIS.

CHEMICAL-FEEDING DEVICE.

976,148.

Specification of Letters Patent. Patented Nov. 22, 1910.

Application filed July 23, 1909. Serial No. 509,214.

To all whom it may concern:

Be it known that I, JOHN E. CAPS, citizen of the United States, residing at Wilmette, in the county of Cook and State of Illinois, have invented certain new and useful Improvements in Chemical-Feeding Devices; and I do hereby declare the following to be a full, clear, and exact description of the invention, such as will enable others skilled in the art to which it appertains to make and use the same.

This invention relates to a novel construction in a device for injecting a measured quantity of chemicals for softening water into water flowing through a pipe, the object being to provide a simple and efficient device of this character which will permit variation at will of the quantity of chemicals introduced, and consists in the features of construction and combinations of parts herein-after fully described and claimed.

In the accompanying drawings illustrating my invention: Figure —1— is a view partly in vertical section and partly in elevation of a device constructed in accordance with my invention. Fig. —2— is a vertical section of the same on the line 2—2 of Fig. —1—.

My present invention is designed particularly for use in connection with the apparatus for heating water forming subject of the application of C. A. Cartwright for Letters Patent Serial No. 488,027, filed April 5, 1909, and has for its particular object to provide means whereby water softening chemical may be introduced into all of the water entering the system from the service pipe. It will be understood that its use is not limited to this particular purpose or in connection with this particular apparatus.

The object of the invention is to provide means whereby a measured quantity of water softening chemical is introduced into a measured volume of water, the latter automatically controlling the feed.

In the drawings A indicates a source of supply of water under pressure from which water passes to the pipe B through the passage C in my device. My said device comprises a suitable frame which includes a cylindrical chamber D in which a water wheel E is revolvably mounted, the shaft F of the latter projecting therefrom and carrying a spur pinion G which meshes with a spur gear H suitably rotatably mounted on the frame. The blades of the said water wheel

E project into the passage C which is disposed tangential with and communicates with said cylindrical casing D, the flowing water serving to rotate said water wheel in a well-known manner.

Extending transversely to the passage C is a pump cylinder I which communicates at one end with said passage C between the ends of the latter. The connection between the pump I and said passage C is controlled by a valve J normally held on its seat by means of a spring K bearing at one end thereon and at its other end against the lower end of a guide member L disposed in a pipe M integral with and extending transversely to the passage C in axial alinement with the pump cylinder I. Said guide member L is integral with the cap N closing said pipe M and is provided with a central guide recess O in which the upper end of the stem P of said valve J is received, said valve being guided partly by the engagement of its stem with the wall of the opening O and partly by the spokes or flanges Q disposed below and integral with said valve. Communicating with said pump between its ends is a pipe R having a check valve S disposed therein and which is connected with a source of supply of chemicals in solution.

The piston T of said cylinder is of the trunk type and is connected by means of the pitman U with the segmentally slotted segmental arm V of a lever pivotally mounted between its ends on a part of the frame of the device, said lever being connected at its other end with the pitman W, the latter being connected with the crank pin X carried by said spur gear H, said lever being oscillated thereby. Mounted on the free end of the segmental arm of said lever is a swivel nut Y through which a set screw Z passes, the latter being revolvably connected at its inner end with a swiveled member 27 disposed on the head 28 at the lower end of said pitman U. On said segmental arm V is a graduated scale the graduations of which are preferably numbered to indicate the different quantities of chemical delivered upon each stroke of the piston when the said head 28 of the pitman is disposed to register with said respective graduations.

The operation of the device is very simple and easily understood from the foregoing description. It will be obvious that water passing through the passage C will rotate the water wheel E and the latter in turn will

rotate the spur gear II and this by its connection with the lever will oscillate the latter and thereby reciprocate the piston T. By moving the head 28 of the pitman U toward or away from the pivot of the lever the stroke of the piston is varied so that varying quantities of chemical will be delivered from said pump into the passage C to commingle with the water flowing through the same.

The drawings illustrate a suitable embodiment of my invention but no attempt has therein been made to adhere to proper relative proportions of the parts; it being understood, of course, that these may be changed and varied without departing from the spirit of the invention.

I claim as my invention:

1. In apparatus of the kind specified, a water supply pipe equipped with a perpendicularly disposed cylindrical arm constituting a pump cylinder, a check-valve controlled inlet for water-softening chemical between the ends of said pump-cylinder, a piston in the latter, a valve controlling the communication of said cylinder with said water supply pipe, a spring maintaining the

same normally closed, a water motor actuated by the passage of water through said pipe, and gearing between said motor and said piston to reciprocate the latter.

2. In apparatus of the kind specified, a water supply pipe equipped with a perpendicularly disposed cylindrical arm constituting a pump cylinder, a check-valve controlled inlet for water-softening chemical between the ends of said pump-cylinder, a piston in the latter, a valve controlling the communication of said cylinder with said water supply pipe, a spring maintaining the same normally closed, a water motor actuated by the passage of water through said pipe, gearing between said motor and said piston to reciprocate the latter, and means interposed in said connection for varying the stroke of said piston.

In testimony whereof I have signed my name in presence of two subscribing witnesses.

JOHN E. CAPS.
